BRUSH ATTACHMENT FOR PHONOGRAPH
PICKUP ARMS

William H. Zimmerman, San Bernardino, Calif.

Application July 6, 1948, Serial No. 37,110

4 Claims. (Cl. 274—47)

1

My invention relates to a brush attachment for phonograph pickup arms, and the objects of my invention are:

First, to provide an attachment of this class which is an improvement over the subject matter of my earlier patent application, Serial Number 739,639, filed April 5, 1947, now Patent No. 2,583,622.

Second, to provide a brush attachment of this class which is very readily and easily clipped onto the end of a conventional phonograph pickup arm;

Third, to provide a brush attachment of this class having a tension spring adapted to tightly hold the attachment in connection with the pickup arm, substantially eliminating vibration intermediate the arm and brush attachment;

Fourth, to provide a brush attachment of this class having a resilient clip provided with novel brush connection means thereon, which is not subject to vibrational disturbance;

Fifth, to provide a brush attachment for phonograph pickup arms of this class which maintains certain brush pressure on the record in the path of the needle thereon, whereby cuttings from the record and dust are efficiently removed from the mechanical grooves in the record, in advance of the needle thereon; and

Sixth, to provide a brush attachment for phonograph pickup arms of this class which is very simple and economical of construction, efficient in operation, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawing and to the characters of reference thereon, forming a part of this application, in which:

Fig. 1 is a top or plan view of a phonograph pickup arm and record, showing my brush attachment for phonograph pickup arms in connection with said phonograph pickup arm; Fig. 2 is enlarged side elevational view of my brush attachment for phonograph pickup arms; Fig. 3 is a fragmentary elevational view taken from the line 3—3 of Fig. 1, showing a portion broken away and in section to amplify the illustration, and Fig. 4 is an enlarged cross-sectional view of my brush attachment for phonograph pickup arms, taken from the line 4—4 of Fig. 1.

Similar characters of reference refer to simi-

lar parts and portions throughout the several views of the drawing.

The clip 1, spring 2, and brush 3 constitute the principal parts and portions of my brush attachment for phonograph pickup arms.

The clip 1 is provided with a U-shaped portion 1a, having opposed arms 1b and 1c, which are each provided with channel-shaped hook portions 1d and 1e, respectively, at their lower edges, arranged to clip over the normally lower channel legs of the phonograph pickup arm A, as shown best in Fig. 4 of the drawing. The upper edge portions 1f and 1g, extend slightly above the upper plane of the phonograph pickup arm

15 A and the spring 2 is provided with eyes at opposite ends thereof extending through the arms 1b and 1c near the edges 1f and 1g, respectively, tending to hold the arms 1b and 1c in tight fitted relationship with opposite sides of the phonograph pickup arm channel A. The engagement

15 of the spring 2 with the top of the phonograph pickup arm A tightly maintains the hooks 1d and 1e in engagement with the lower edges B and C of the channel-shaped pickup arm A, all as

20 shown best in Fig. 4 of the drawing. Integral with the U-shaped portion 1a is a resilient flat arm portion 1h, vertically resilient, on which the brush 3 is supported. This brush 3 is provided

25 with bristles 3a embedded in a solid plastic hub 3b, having a shoulder 3c abutted to the arm 1h at its reverse folded portion 1j which is provided with a pair of cylindrically formed openings 1k and 1m on an acute angle relatively to each other, wherein the hub 3b of the brush 3 is frictionally engaged, all as shown best in Fig. 3 of the

30 drawing. It will be here noted that the shoulder 3c of the brush 3 abuts the cylindrically formed opening 1m, whereby positive vertical location of the brush 3 is maintained relatively to the arm 1h of the clip 1.

The operation of my brush attachment for phonograph pickup arms is substantially as follows: When the record D rotates, the needle on the pickup arm A follows the path indicated by the dash lines E, the brush 3 traverses the same

35 general path, overlapping the track of the needle, very efficiently covering the area immediately traversed by the needle over the spiral track in the record. The arm 1h of the clip 1, being

40 resilient in character, provides a certain amount of tension on the brush 3 for positively engaging the same with the upper track surface of the record D, while the spring 2 maintains the arm portions 1b and 1c in firm engaged relationship with

45 opposite sides of the channel-shaped in cross-

50

section phonograph pickup arm A, all as shown best in Fig. 4 of the drawing. It will be here noted that the spring 2 permits support of my brush attachment in connection with the pickup arms of varying widths and elevations, while the arm 1h may be deflected either up or down to place the brush 3 at the plane of the record.

In the views of the drawing, I have shown the attachment formed from a thin flat material which lends itself to punch press manufacture. Any resilient metal which may be treated to provide the brush supporting arm with sufficient pliancy to permit the same to be placed in a number of positions of adjustments relative to the record face may be used.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. A brush attachment for a phonograph pickup arm having lower edges comprising a clip having spaced arms, one end of each arm being connected by a curved portion, the spaced arms engageable with opposite sides of the phonograph arm, a channel-shaped hook formed along one edge of each of said spaced arms at the free ends thereof and engageable with the lower edge of the pickup arm; a spring connected between said spaced arms opposite the hook thereon for forcing the arms into engagement with the opposite sides of the pickup arm a brush holding arm having one end thereof secured to and extending from the curved portion of the clip and capable of adjustment toward and away from the longitudinal axis of the phonograph pickup arm; and a record cleaning brush mounted in the outboard end of the brush holding arm, the adjustment of the brush holding arm determining the pressure applied by the brush to the record.

2. A brush attachment for a phonograph pickup arm having lower edges comprising a clip having spaced arms, one end of each arm being connected by a curved portion, the spaced arms engageable with opposite sides of the phonograph arm, a channel-shaped hook formed along one edge of each of said spaced arms at the free ends thereof and engageable with the lower edge of the pickup arm, a spring connected between said spaced arms opposite the hook thereon for forcing the arms into engagement with the opposite sides of the pickup arm, a resilient brush holding clip secured to and extending from the curved portion; and a brush in said clip engageable with a phonograph record

for cleaning the sound groove thereon, the brush holder adjustable for determining the pressure between the brush and record cleaned thereby.

3. A brush attachment for a phonograph pickup arm needle and having lower edges, comprising a pair of spaced arms connected by a curved member for fitting about the free end of the pickup arm, channel-shaped hook members formed along one edge of each of the spaced arms at the free ends thereof and engageable with the lower edge of the pickup arm, a spring connected between the spaced arms at the free ends thereof and opposite the hooks thereon for drawing the spaced arms into engagement with opposite sides of the pickup arm, an adjustable resilient brush holding clip having one end thereof secured to and extending from the curved portion of the attachment, said clip embodying a return bend portion at the outboard end thereof; and a brush secured in the return bend free end of said clip and disposed to engage the groove in a phonograph record in circular alignment with the phonograph needle, the degree of adjustment determining the pressure between the record and pickup arm.

4. A brush attachment for a channel-shaped phonograph pickup arm provided with lower edges and having a phonograph record groove engaging needle thereon comprising a clip having a pair of spaced arms, one end of each arm connected by a curved portion, the clip fitting about the free end of the phonograph arm, a hook formed along one edge of the free ends of each spaced arm and engageable with the lower edge of the phonograph arm, a spring connected between said spaced arms for drawing them into engagement with opposite sides of the phonograph arm when the clip is fitted over the free end thereof, a brush clip secured to and extending from the curved portion thereof and having an apertured return bend thereon, the free end of which engages the body of the brush clip, a brush hub held in the aperture in the return bend, the apertured return bend being so disposed that the brush hub is substantially the same distance from the center of rotation of the needle groove as is the needle; and brush bristles in said hub engageable with a phonograph record.
